(57) **CLAIM**

The ornamental design for a handle for a gaming machine, as shown and described.

DESCRIPTION

FIG. 1 is an isometric front view of the handle for a gaming machine;

FIG. 2 is an isometric rear view of the handle for a gaming machine;

FIG. 3 is a front view of the handle for a gaming machine;

FIG. 4 is a rear view of the handle for a gaming machine;

FIG. 5 is a right view of the handle for a gaming machine;

FIG. 6 is a left side view of the handle for a gaming machine;

FIG. 7 is a top plan view of the handle for a gaming machine, wherein the bottom plan view is a mirror image thereof; and,

FIG. 8 is a front view of the handle for a gaming machine in an environment of use.

The broken lines showing a handle for a gaming machine and gaming machine in FIG. 8 depict environmental subject matter and form no part of the claimed design.
